[57] CLAIM

The ornamental design for a ball tossing game device, as shown and described.

DESCRIPTION

FIG. 1 is a front perspective view of a ball tossing game device showing our new design;

FIG. 2 is a front elevational view of FIG. 1; the side and rear views being essentially identical thereto;

FIG. 3 is a top view of FIG. 1; and,

FIG. 4 is a bottom view of FIG. 1.
